MANUFACTURE OF INCANDESCENT
ELECTRIC LAMPS

Orrick H. Biggs, Beverly, and Lewis E. Cobb,
Marblehead, Mass., assignors to Hygrade Syl-
vania Corporation, a corporation of Massachu-
sets

Application January 21, 1931, Serial No. 510,110

6 Claims. (Cl. 91—70)

This invention relates to incandescent electric lamps and to methods of making them.

An object of the invention is to provide the envelope of a lamp or similar hollow article with a spray-coating of refractory translucent material, over a predetermined localized area on the interior of the article, in such a manner that the edge of the coating provides a sharply defined linear boundary between the coated and uncoated portions.

It is a common practice to etch or frost the outer surface of the bowl portion of an electric lamp bulb to produce what is commonly known as a "white bowl" effect. In other words, this part of the bulb is no longer clear and transparent but is made translucent so that the glare is reduced and the lamp gives a softer and more diffused light. This effect, also, is sometimes obtained by coating the bowl externally with some kind of a translucent material. Both of these methods, however, are objectionable in that the outer surface of the bulb thereby is rendered sufficiently rough to cause dust and dirt to cling to it, thus reducing the illumination afforded by the lamp. This is particularly true if the frosted or coated area becomes moistened at all with oil or with dust of a sooty nature, as frequently happens in factories and industrial plants.

This fact has been recognized heretofore and attempts have been made to frost or coat the inside of the bulb. The frosting operation when performed internally is too expensive to be practical, at least by present methods, and the coating process has proved to be so difficult to control that it has never gone into practical use, so far as we are aware.

The present invention deals with this problem and it aims to devise a thoroughly satisfactory solution for it.

The nature of the invention will be readily understood from the following description when read in connection with the accompanying drawings, and the novel features will be particularly pointed out in the appended claims.

In the drawings,

Figure 1 is a perspective view of an apparatus embodying features of this invention, and designed for use in practicing the method of this invention;

Fig. 2 is a similar view on a larger scale but showing only the lamp bulb and spray gun;

Figs. 3 and 4 are plan and perspective views, respectively, of a spray nozzle equipped with a shield constructed in accordance with this invention;

Fig. 5 is a side view illustrating a later step in the method;

Fig. 6 is a side elevation showing another embodiment of the invention; and

Fig. 7 is a similar view illustrating a somewhat different arrangement embodying features of this invention.

According to the method provided by this invention the coating material is sprayed on the inner surface of a portion only of the lamp, and the spray is very definitely controlled at the margin of the coated area. It usually is preferable to produce a relatively clear line of demarcation between the coated and uncoated areas, and the invention provides an apparatus with which this result can be accomplished. As above indicated, it is usually desirable to coat only the rounded end portion or bowl of the lamp bulb, this portion being indicated approximately by the white area 2 in Figs. 1 and 2, and the cone 3 and neck 4 of the bulb are left clear or uncoated. In some cases, however, it is desirable to coat the cone or skirt portion 3 and to leave the bowl 2 uncoated, a lamp so treated often being referred to as a "skirt coated" lamp. This invention provides means for accomplishing this result also. The coating material used may be of any suitable nature, such for example, as those materials heretofore used for internal coatings. They should be capable of producing a highly refractory translucent coating so that the presence of the coating on the inner surface of the bulb will not materially reduce the life of the lamp or adversely affect its operation in any way. A typical coating composition consists essentially of water glass (sodium silicate), water, and pigment.

A convenient form of apparatus for producing white bowl effects according to this method is illustrated in Fig. 1. It comprises a rotating head 5 having spring fingers 6 to grip the lamp bulb, and mechanism enclosed in the casing 7 for revolving the head and the lamp around approximately the axis of the lamp bulb. The neck of the lamp is steadied during this operation by three rolls 8 which engage the outer surface of the neck and are supported on a bracket 9. The coating material preferably is applied by a spray gun 10 which may be of any suitable type, the particular gun shown being of a common commercial form. It includes a control lever or trigger 12, a relatively long shank 13 to reach well into the lamp bulb, and a spray nozzle 14. This nozzle includes opposed air outlets 15, Fig. 4, located at opposite sides of another outlet 16 for the paint or other coating material. This is the

usual arrangement and it produces a fan-like spray.

In using this apparatus the spray nozzle is inserted in the bulb in approximately the position shown in Figs. 1 and 2, and the spray is turned on while the bulb is revolved by the head 5. Preferably the nozzle is advanced along substantially the path indicated by the dotted line 17, Fig. 2, and is moved back and forth in this path 10 several times during the spraying of a single bulb so that the entire inner surface of the bowl will be covered. This traversing movement may be produced either by hand or by automatic machinery, as desired.

15 As above indicated, it usually is preferable to have the coated portion of the bulb separated sharply from the uncoated area. The nature of the spray is such that it will not produce a sufficiently clear edge bounding the coated area, but 20 we have found that such an edge can be produced by equipping the spray nozzle with a shield such as that shown at 18. This shield may consist of sheet metal bent as shown, and including a split clamp 19 for securing it on the shank 13 of the 25 spray gun. It is so shaped as to intercept or cut off one edge of the fan-shaped spray sharply. With this arrangement, therefore, it is possible so to control the spray that the coated area will be terminated by a fairly definite edge or margin. 30 The coating material intercepted by the shield 18 tends to collect on the shield and run down to the lower edge and drop off. In order to prevent this action we have bent over the lower edge of the shield, as shown at 20, to form a trough 35 extending along this edge which serves to catch and hold such material. It will be understood that the period of time required to coat an individual bulb is very short indeed, so that this trough is not required to hold any great volume 40 of liquid before it is withdrawn from the bulb, the spray first being shut off.

In using those coating materials which we have tried the best results are produced by heating the bulb during the spraying operation, and a 45 burner is indicated diagrammatically at 21, Fig. 1, for this purpose. The heat causes the spray to dry on the glass surface almost as soon as it strikes it. If a water glass paint or coating material of the character above described is used, 50 the heat has the effect of converting the coating into a very refractory deposit which neither affects adversely the operation of the lamp nor is itself adversely affected by such operation. It is contemplated, however, that some kinds of coating material may make this expedient unnecessary.

55 After the spraying operation has been completed and the bulb has been removed from the rotating head 5, it will be found that small particles of the spray still adhere to the cone and neck of the bulb. We find, however, that these particles can be removed by washing or flushing the inner surface of the bulb with water. This operation may be performed by placing the bulb 60 over a washing nozzle 22, Fig. 5, of a common form. The water issues from the holes in this nozzle at a considerable velocity in the form of a spray which has sufficient force to wash away the 65 small particles of coating material which adhere to the cone and neck of the bulb, but does not remove any material part of the white bowl coating.

An arrangement better suited to automatic operation is illustrated in Fig. 6 in which the spray

gun 13 is mounted in an upright position, this gun being of the same construction as that shown in Figs. 1 to 4, inclusive. It is equipped, however, with a shield 24 which is secured on the shank 13 of the spray gun by a clamp 25. This shield cuts off the edge of the spray in the same manner as does the shield 18 so that the spray at the margin of the coated area is definitely controlled. The small proportion of the coating material which strikes the surface of the shield 24 and runs down the inner surface of the shield is carried away by a tube 26 which extends along the shank 13 of the spray gun and empties into an annular trough 27 secured to the gun at the base of the shank 13. A rubber tube 28 drains this overflow from the trough 27. The side edges of the shield are slightly rolled to guide the drip into the tube 26.

5 10 15 20 25 30 35 40 45 50 55 60 65 70 75 80 85 90 95 100 An apparatus suitable for skirt coating lamp bulbs is shown in Fig. 7. It includes a spray gun like that shown in Figs. 1 to 4, mounted in an upright position, and equipped with a shield 30 which is shaped to cut off the upper edge of the fanlike spray instead of cutting off the lower edge, as does the shield 24. The shield 30 is 25 equipped with a clamp 31 by means of which it is secured in the desired position on the spray gun. It will be clear from an inspection of Fig. 7 that in this arrangement the spray is confined to the skirt portion of the lamp, the bowl portion 30 being left substantially clear.

In using both of the arrangements shown in Figs. 6 and 7 the lamp should be heated, as shown for example in Fig. 1. It will be understood, also, that the lamp and nozzle are relatively revolved in using both the arrangements shown in Figs. 6 and 7. Also, that the lamp may be washed afterwards in substantially the manner illustrated in Fig. 5 to remove any loose coating material.

We have found in practice that the invention provides an entirely satisfactory means for producing a white bowl effect, for skirt coating, or for internally coating any specified area of a lamp bulb and either leaving the remaining area 45 clear or coating it with a different color. The finished product meets the demands of the trade and it can be produced at an entirely reasonable expense.

50 While we have herein disclosed the preferred method of procedure and a preferred form of apparatus for practising the invention, it will be understood that the method may be practised successfully with the aid of other forms 55 of apparatus.

Having thus described our invention, what we desire to claim as new is:

1. The method of making an electric lamp bulb with a refractory translucent coating on a restricted area of the inner surface of the bulb, which comprises inserting a spray nozzle with a shield positioned to intercept a predetermined portion of the spray within the bulb, rotating the bulb and spray nozzle relatively to each other, and diverting the excess spray material away from contact with the bulb.

2. The method of making an electric lamp bulb with a refractory translucent coating on a predetermined restricted area of the inner surface of the bulb, which comprises inserting a spray nozzle with a shield within the bulb with nozzle and shield positioned to project a fan-like spray on a strip only of said restricted area, the spray being projected mainly at an angle 75

to the longitudinal axis of the bulb and being intercepted by the shield to cut off the spray sharply at one edge while diverting excess spray material away from contact with the bulb, and 5 rotating the bulb and spray nozzle relatively to each other to complete the coating of said restricted area.

3. The method of making an electric lamp bulb with a refractory translucent coating, which 10 comprises selecting a restricted area on the inner surface of the bulb to be coated, inserting a spray nozzle with a shield into the bulb with the nozzle and the shield positioned to project the spray material on only a strip of said selected 15 area while diverting excess spray material away from contact with the bulb, and rotating said spray nozzle and bulb relatively to each other to complete the coating of said restricted area.

20 4. The method according to claim 1 in which

the bulb is heated over said restricted area while said restricted area is being sprayed.

5. An electric lamp bulb having a coating of sprayed translucent refractory material on a predetermined restricted area of the inner surface of the bulb the boundary of the restricted area being substantially uniform and determined during the spraying as set forth in claim 1.

6. The product of the process of claim 1 comprising a lamp bulb with a spherical bowl portion and a reduced neck portion the inner surface of the bowl having a refractory translucent coating over a predetermined restricted area on the inner surface of the bowl the boundary line of demarcation between said restricted 15 coated area of the bowl and the uncoated area having a sharpness characteristic of the said process.
